HANDLE FOR A BURIAL CASKET

Peter Schladermundt, Bronxville, N. Y., assignor to National Casket Company, Incorporated,
Oneida, N. Y., a corporation of New York

Application January 21, 1950, Serial No. 7,387

Term of patent 14 years

(Cl. D19—2)

To all whom it may concern:

Be it known that I, Peter Schladermundt, a citizen of the United States of America, residing at Bronxville, county of Westchester and State of New York, have invented a new, original, and ornamental Design for a Handle for a Burial Casket, of which the following is a specification, reference being had to the accompanying drawing, forming part thereof.

Fig. 1 is a front elevational view of a handle for a burial casket, showing my new design, the handle bar being broken away to indicate indefinite length.

Fig. 2 is an edge view thereof.

Fig. 3 is a similar view, with parts being broken away and with a part shown in open position.

I claim:

The ornamental design for a handle for a burial casket, substantially as shown.

PETER SCHLADERMUNDT.
